Application September 13, 1939, Serial No. 294,784

16 Claims. (CL 260—668)

This invention relates to the conversion of hydrocarbon stocks boiling within, and in some cases within and somewhat above, the gasoline boiling point range to high grade motor fuel by catalytic aromatization under critically defined conditions.

It is known that by the use of certain catalysts naphthenic hydrocarbons can be converted into aromatic hydrocarbons with or without the presence of hydrogen. It is also known that at approximately atmospheric pressure in the absence of hydrogen, paraffinic hydrocarbons can be converted into aromatic hydrocarbons by the use of certain catalysts. It has also been known for years that destructive hydrogenation under high pressures and in the presence of large amounts of added hydrogen will produce motor fuels which contain a limited amount of aromatics and which have a relatively high octane number from stocks boiling well above the gasoline boiling point range, but such processes have not made appreciable commercial headway because of the expense of building and operating a hydrogenation unit which operates at extremely high pressures (not to mention the expense of producing or supplying the necessary hydrogen) and because of the undesirable increase in volatility and the production of hydrocarbon gases.

An object of our invention is to obtain the advantages of all of these previous processes without suffering their inherent disadvantages by means of an improved endothermic dehydro-aromatization process.

Prior to our work no commercially practicable process for the conversion of aliphatic, particularly paraffinic, hydrocarbons boiling within and slightly above the motor fuel range to motor fuels of high aromatic content has been developed. In the course of a very great amount of experimental work we have found that under critically defined conditions stocks boiling within, and sometimes slightly above, the gasoline boiling point range can be converted into unusually high yields of aromatic hydrocarbons boiling within the gasoline range, at the same time accomplishing a number of advantages not achieved by the prior art.

It is an object of our invention to provide a process for the conversion of aliphatic hydrocarbons to aromatic hydrocarbons. It is a further object of our invention to provide a process for the conversion of a stock boiling approximately within the gasoline boiling point range, and rich in aliphatic hydrocarbons, into high yields of a highly aromatic motor fuel. It is a particularly important object of our invention to provide a catalytic aromatization process which produces extremely small amounts of coke and gives long catalyst life. Other and more detailed objects, advantages and uses of our invention will be

come apparent as the description thereof proceeds.

We have found that in order to overcome the disadvantages of the prior art and achieve the objects above enumerated, it is necessary to control a large number of operating variables within closely and critically defined limits; for instance, we find that the severity factor, which term we will later define, must be great in order to achieve the production of aromatics from paraffinic hydrocarbons and such olefinic hydrocarbons, if any, as may be present. At the same time we find that the severity factor must not be excessive or adverse influences come into play.

Concurrently with control of the severity factor, we also find that pressure in conjunction with added hydrogen must be used to decrease coke formation and increase octane number of the product but that the use of higher pressures such as those used in destructive hydrogenation are markedly disadvantageous because they decrease the yield of olefins and particularly aromatics and decrease, therefore, the octane number of the product since the result is an hydrogenation process rather than a dehydrogenation process such as we have devised. Further we find that the pressure must be critically controlled since if this is not done light paraffins are produced which, if gaseous, reduce the liquid yield, and if liquid and having less than six carbon atoms cannot be aromatized thus limiting the octane number to the relatively low value characteristic of paraffins.

In spite of the fact that our process is very definitely one of dehydrogenation and aromatization rather than hydrogenation, we find it very important, likewise in conjunction with the other noted factors, to use critically controlled amounts of hydrogen which are in general considerably less than are used in hydrogenation processes. The use of hydrogen cuts down coke formation and greatly increases the length of run possible. Further, the use of hydrogen up to a certain low figure gives an important improvement in the octane number of the product but beyond that figure the octane number begins to drop off. Thus we have found that there is an optimum amount of hydrogen to be used (but not consumed) and that this optimum varies with the severity of treatment as expressed by the severity factor.

As to the catalysts used in our process, we prefer the oxides of the metals of the left-hand column of group VI of the periodic table, particularly chromium, molybdenum and tungsten but we can also use other metallic oxides and other metallic compounds, particularly oxides of the metals of the left-hand columns of groups IV and V of the periodic table such as titanium, cerium, thorium and vanadium. Moreover, while these catalytic oxides can be used alone or on various

supports including magnesia, we find it very highly preferable to utilize them on alumina, particularly an activated alumina or on alumina gel, as a support and in general the catalytic oxide or other catalytic compound should be the minor constituent, usually from 1 to 40% by weight of the total catalyst including the support, although the optimum percentage varies, of course, with the catalyst used. It will also be apparent that mixed catalysts can be used, for instance a mixture of chromium oxide and molybdenum oxide alone or preferably on an alumina support, and in this case the active catalytic oxides should be from about 1 to about 25% by weight of the total catalyst. Another catalyst which can be used is magnesium chromite either alone or on a suitable support, preferably alumina. In fact, any aromatization catalyst or material that promotes the dehydrogenation and cyclization of aliphatic hydrocarbons can be used. As those skilled in the art know, the efficiency of a given catalyst is largely determined by its method of preparation and consequently some catalysts give better results than others under a specific set of conditions. Such differences obviously can be overcome to some extent by suitable slight alterations in the operating conditions within the limits taught in the present specification. However, of all these catalysts we greatly prefer to use a catalyst comprising molybdenum oxide supported on alumina, particularly activated alumina, and the molybdenum oxide should most advantageously constitute from about 2 to about 10% by weight of the total catalyst since this has been found to include a very sharp optimum range which gives the best results. Larger amounts of molybdenum oxide can, however, be used.

We greatly prefer that our catalyst be substantially sulfur free since sulfide catalysts as contrasted with oxide catalysts tend to degrade the stock to less valuable light paraffins and lead to predominant hydrogenation rather than predominant dehydrogenation, i. e. hydrogen consumption instead of hydrogen production. These sulfide catalysts also result in increased coke production.

Our preferred catalyst used in the experiments to be described in connection with Tables 1 through 5 which will be given later was a molybdenum oxide on activated alumina catalyst and more particularly was made in accordance with the following procedure:

Dissolve 165 kilograms of ammonium paramolybdate in sufficient distilled water to yield 1500 liters of solution. Place 1500 kilograms of granular activated alumina in an apparatus which can be evacuated and add the molybdate solution. Agitate the mixture and then apply a vacuum pump and reduce the pressure to 30-40 millimeters of mercury. Then allow the pressure to rise to atmospheric. Lower the pressure a second time to the same level and then allow it to rise again to atmospheric pressure. Repeat this procedure a third time and then drain the remaining liquid from the impregnated alumina. Air-dry the latter on screens or other suitable containers using layers of about one inch in depth. At the end of this time place the dried material in a furnace in a suitable container and heat it at a temperature of 1200° F. for one hour. Cool to atmospheric temperature and store in closed containers until ready for use.

While it can be calculated from the quantity of solution absorbed that the catalyst should con-

tain 3.75% MoO_3 by weight, actual analysis shows the presence of about 6% of molybdenum oxide, this difference resulting, no doubt, from preferential adsorption of the molybdenum compound from the solution. In any event the difference in effect between a catalyst containing 3.75% of MoO_3 and one containing 6% is negligible.

As previously indicated, the oxide catalysts are preferred but in some cases, such as our preferred molybdenum oxide catalyst, the oxide tends to be reduced in the process and in general instead of using the oxides of the metals of the left-hand columns of group IV, V and VI, the metals themselves can be used, preferably supported on alumina.

Our invention will be described further with reference to the accompanying drawings which form a part of this specification and in which:

Figure 1 is a plot of the area of severity factor, temperature and time factor in which we find it necessary to operate our process, the cross-hatched area being preferred;

Figure 2 is a plot of the relationship between severity factor and octane number, which like Figures 3 to 7 is particularly applicable to a particular charging stock and catalyst; but is representative of more general results;

Figure 3 is a plot of the relationship between the content of aromatic hydrocarbons in the product from our process and octane number of this product;

Figure 4 is a plot of the effect of increasing severity factor on the amounts of aromatic and olefinic hydrocarbons in the product;

Figure 5 is a plot of the effect of increasing severity factor on the A. P. I. gravity of the product;

Figure 6 is a plot of the effect of the operating pressure on the amount of coke formed and on the octane number of the product;

Figure 7 is a plot of the effect of the mol ratio of hydrogen to charge on the amount of coke formed and on the octane number of the product;

Figure 8 is a plot of the relationship between the operating variables severity factor and mol ratio of added hydrogen and shows the area in which we find it essential to work, the preferred area being cross-hatched;

Figure 9 is a simplified flow diagram showing a stationary bed type of apparatus which can be used in accordance with our invention;

Figure 10 is a simplified flow diagram of a moving bed type of apparatus which can be used in accordance with our invention;

Figure 11 is a detail of the apparatus for introducing catalyst and feed into the reaction chamber of Figure 10; and

Figure 12 is a detail of the apparatus for removing catalyst and products from the reaction chamber of Figure 10.

One of the important operating variables in our process is time factor which may be defined as the amount of time in hours required to put through the catalyst a volume of feed (measured as liquid) equal to the volume of the catalyst chamber, the volume of the catalyst chamber being the over-all volume of that portion of the chamber which is filled with the catalyst. In other words, time factor is the volume of catalyst space divided by the feed rate in volumes per hour. In determining this ratio, the term "volume of catalyst space" obviously refers to a space completely filled with the catalyst particles and having a density corresponding to that which

the particles assume after introduction into the reaction zone, that is the "apparent" or bulk density. The designated volume, therefore, includes a certain volume of voids between the particles. If the effective quantity of catalyst material present in a unit volume is substantially reduced by extending the distance and increasing the voids between adjacent catalyst particles by mixing the active catalyst material, with inert particles or otherwise, a suitable correction should be applied to compensate for the decreased concentration of active catalyst material in unit volume of catalyst space thus effected as will be obvious to those skilled in the art. We have found that the time factor should be between 0.1 and 25 and preferably between 0.2 and 20 hours. Time factor or its reciprocal, the space velocity, is the important factor rather than contact time. Contact time, in the usual sense, is a calculated value intended to be the average length of time during which any given part of the charge is in contact with the catalyst. This is entirely unsatisfactory to calculate since it depends on factors which can only be estimated, one of the most serious difficulties in figuring contact time being the fact that the time which is really significant is the time an average molecule is present in an adsorbed film on the catalyst. Calculated contact times have been found to be entirely insignificant and cannot be correlated with the results obtained in our process. This is particularly true because we choose to circulate hydrogen with the hydrocarbon charge.

Not only is time factor important but temperature is likewise important and should be at least 875° F. and preferably at least 890° F. On the other hand, the maximum temperature is likewise significant and should be not over 1075° F. If the temperature is lower than the minimum specified the reaction is unsatisfactorily slow and does not produce the desired high yield of aromatic hydrocarbons from paraffinic hydrocarbons. On the other hand, if the maximum is exceeded an excessive amount of gas is produced. In other words, operating below the specified lower limit tends to give a condition favorable to hydrogenation which is definitely not desirable in our process. At the same time when the temperature is higher than the upper limit, thermal reactions become excessive.

When we speak of temperature in this specification and in the appended claims we refer to the temperature as measured in the catalyst bed unless some other meaning is indicated. The catalyst bed temperature to which reference is made is the weighted average temperature calculated from temperature measurements made at a plurality of representative points in the catalyst bed.

In addition to the importance of the time factor and temperature, the relationship between these two variables must likewise be maintained within critical limits. We refer to this relationship as severity factor and define the severity, S, as

$$S = T + 100 \log_{10} F$$

Where T is the temperature in degrees fahrenheit and F is the time factor in hours. This equation defines severity in such terms that with a given charging stock and other process conditions being held constant, all runs using a given severity factor will give approximately the same octane number product. Since the high octane number of our product is due largely to its high

content of aromatic compounds, it may be said that the content of aromatics is a function of severity factor and a certain minimum severity factor must be preserved in order to secure the beneficial results flowing from our process. With extremely active catalysts this minimum severity factor can be about 925 but in order to obtain the best results the minimum severity factor should be 950 or 975. At the same time if either the time factor or the temperature is too high, unsatisfactory results are obtained and there is thus a critical maximum as well as a critical minimum on severity and this maximum is 1100 or, for best results, 1075. The area of temperature, time factor and severity in which we find it desirable and necessary to work in order to achieve our results, is shown in Figure 1. The diagonal lines extending across this area are lines of constant severity and the numbers on them are the severities as above defined. The cross-hatched area is that which is preferred.

One striking illustration of the results of high severity is shown in Table 1 in which with a severity of 1067 and the other conditions shown an octane number of 91.3 was obtained charging a stock with an octane number of 42.3. This is an octane number increase of 49 points compared with an increase of perhaps 10 or 12 points for an ordinary dehydrogenation process. The data shown in Table 1, like all the rest of the data in this specification, with one exception, were obtained using apparatus of the type shown in Figures 10, 11 and 12. As in all of Examples Nos. 1 through 12, the catalyst was the specific molybdenum oxide on alumina catalyst above described, and the charging stock was an East Texas heavy naphtha having an A. P. I. gravity of 50.3°, containing approximately 14% aromatics, 33% naphthenes and no olefins, the remainder being largely paraffin hydrocarbons. This naphtha had an initial boiling point of 248° F., a 50% boiling point of 310° F. and an end point of 396° F. The original octane number measured by the Cooperative Fuel Research Motor Method, as were all the octane numbers mentioned herein, was 42.3.

¹ Fixed bed run.

² Length of run.

It will be seen from the foregoing table that octane number of product decreases rather rapidly with decreasing severity factor although yield increases somewhat at the same time. The exact quantitative relationship varies to some extent with the charging stock, the catalyst and with other operating conditions.

As previously mentioned, the high octane number of the product is due largely to the very high content of aromatic hydrocarbons and this is illustrated in Figure 3 which shows the content of aromatic hydrocarbons as a function of octane number. This curve was plotted from a large number of runs using the East Texas heavy naphtha charging stock to which reference has previously been made. We can, of course, plot aromatic content against severity factor instead of against octane number and this is done in Figure 4 which was prepared largely from the data of Table 2. It is interesting to note that not only does our high severity result in very high aromatic content but it also results in low olefin content in the product as is also shown in Figure 4. While with severity factors lower than those which we use the olefin content of the product is often higher than that of the charge (assuming a charge low in olefins), it will be seen that with the severity factors which we use the olefin content is actually decreasing with increasing severity (or increasing octane number). The amount of olefins relative to paraffins in the product for this particular naphtha tends to reach an equilibrium with the olefins at 29% of the total olefins plus paraffins so that as aromatics are produced in large quantities, thereby decreasing paraffins, olefins are decreased. Thus we have a dehydrogenation process which produces very little olefins and in fact converts olefins, if present, as well as paraffins to very large yields of aromatics.

The A. P. I. gravity of the product is a good rough index of its content of aromatic hydrocarbons since aromatics have low A. P. I. gravities or, in other words, high specific gravities. Figure 5 shows an average plot of octane number versus A. P. I. gravity for products from a large number of runs including all those given in the examples in this specification and shows that with increasing octane number the gravity tends to drop off and in any event the gravity of this stabilized product is less than, and for the more desirable severity factors usually at least 3° A. P. I. less than, the gravity of that part of the original charge having the same end point as the end point of the product. As a matter of fact, in spite of there being some material formed that boils below the initial boiling point of the charging stock, the gravity of the whole product in degrees A. P. I. is practically invariably less than that of the whole charging stock (even if the product contains material boiling above the gasoline line boiling point range) when working under the conditions which we have determined. This is true even though increasing A. P. I. gravity ordinarily accompanies increasing volatility thus partially offsetting the gravity effect resulting from the production of aromatics.

The low A. P. I. gravity of the gasoline made in accordance with our invention means that the customer gets more pounds per gallon as well as a better product.

While temperature, time factor and more particularly severity are very important in order to achieve the results of our process, still other factors are of very great importance.

For one thing pressure likewise must be kept within a critical range. A number of processes have been described in the literature and in prior patents for carrying out aromatization reactions with some of the same catalysts which we have described but under atmospheric pressure and while the results are interesting as laboratory runs they are not of commercial interest due to the fact that the catalyst is very rapidly fouled by the deposition of coke and other carbonaceous matter so that the length of run in stationary bed operations or the catalyst holding time in moving bed operations is very uneconomically low under these conditions. We have found that not only does the use of moderate pressures very markedly decrease the amount of coke deposition and increase the length of run or, what amounts to the same thing, the catalyst holding time but the use of pressure, within certain limits and in the presence of hydrogen, increases the octane number of the product. The effect of increasing the pressure from atmospheric to 30 pounds per square inch gage in a pair of comparable runs was to increase the octane number of the product from 57.8 (atmospheric pressure) to 63.2 (30 pounds per square inch). While these octane numbers are low due to the fact that the temperature (842° F.) and severity (902) are well below our range, the difference in octane number of product (5.6) between these two runs illustrates one very important advantage using pressures of at least about 30 pounds per square inch gage.

Further increases of pressure (below certain limits) are still more advantageous and we prefer to use pressures of 50 to 300 pounds per square inch gage although good results can be obtained at from 30 to 375 or in some instances even 450 pounds per square inch gage. Naturally, the exact pressure will vary depending upon the

severity factor, the charging stock and the catalyst employed. The pressure referred to represents the total vapor pressure due to the added hydrogen and vaporized naphtha charge, that is the sum of the partial pressures of the hydrogen and naphtha vapor in the reaction zone.

In the following table Examples 6 and 7 illustrate the effect of raising the pressure from 30 to 100 pounds per square inch gage (2.9 point increase in octane number) and Examples 8 and 9 illustrate the effect of raising the pressure from 100 to 200 pounds per square inch gage (0.6 point increase in octane number), each pair of data being under otherwise comparable conditions.

Figure 6 illustrates for typical conditions the effect of pressure on the amount of coke and also on octane number. These curves are plotted in part from the data of the examples given in this specification and in part from additional data and trends. It will be noted that while raising the pressure increases the octane number at first, this increase flattens off at about 200 or 250 pounds per square inch gage and finally tends to decrease in spite of the fact that increased pressure at a given time factor inevitably means an increase in the time during which a given particle of the charging stock is in contact with the catalyst.

While we prefer to charge straight run naphthas to our process, cracked naphthas can also be charged and in this event we prefer pressures of about 30 to 100 pounds per square inch and in any event not over about 250 pounds per square inch since at a pressure of the order of 300 pounds per square inch there is a considerable tendency (with cracked stocks) to consume hydrogen instead of producing it.

Another very important consideration in achieving the results of our process is careful control of the amount of hydrogen. We measure the amount of hydrogen in terms of mol ratio which appears to be the most significant measure. The mol ratio of hydrogen is figured as the number of mols of hydrogen per mol of charge calculated on the basis of the mean molecular weight of the charge which for the East Texas heavy naphtha used in the examples is in the vicinity of 120.

The use of small amounts of hydrogen cuts down the formation of coke very markedly and thereby increases the length of runs or on-stream periods to the point where regeneration is not necessary at the frequent intervals which would otherwise be essential. Thus lengths of runs from 25 to 100 hours with the stationary

catalyst bed can be used in our process or when using moving bed the catalyst holding time, i. e. the time the catalyst is in the reaction chamber, is of the same general magnitude. As applied to stationary bed work the term catalyst holding time can be used to refer to the length of run. Following the period during which the catalyst is in the chamber (which may be very short or may be as long as about 100 hours) the catalyst must be regenerated which can be done by known means using air diluted with flue gas or using some other oxygen containing gas as will later be described in connection with the flow diagrams.

While we achieve long catalyst on-stream periods with satisfactory conversion as compared with prior art processes for aromatizing paraffin hydrocarbons, we definitely avoid the use of the high pressures and high hydrogen concentrations necessary in order to achieve hydrogenation conditions since with such conditions the desirable highly aromatic product is not obtained. Moreover, if these high pressure-high hydrogen concentration conditions are used, the process becomes one of hydrogenation and consumes hydrogen whereas our process produces net hydrogen. A still further differentiation is that in a destructive hydrogenation process there is inevitably a very large degradation of the charge or, in other words, the product is generally much more volatile than the charge whereas in our process the production of volatility is definitely limited and this extreme degradation is avoided. In our process the 50% boiling point of the charge and the 50% boiling point of the total liquid product are within 75° F. and usually within 50° F. of each other so that the degradation and volatility production are relatively small or even non-existent.

It is interesting to note, reverting to the matter of the ratio of hydrogen to hydrocarbon charge, that the improvements in octane number obtainable by using small concentrations of hydrogen are contra to what might logically be expected since when other conditions are held constant dilution of the charge with hydrogen results in decreasing the contact time and therefore one would expect to obtain results comparable to a lower time factor whereas actually the effect of adding hydrogen within certain limits is to improve the octane number just as increasing time factor (and thereby increasing severity factor) improves it.

At the same time, as previously pointed out, it is important to keep the hydrogen concentration within definite, rather low limits since a point is reached at which raising the hydrogen concentration decreases instead of increasing the octane number. This is shown by Figure 7 in which a typical set of data is plotted to show this optimum and a line is shown giving the approximate locus of this optimum for different severities.

Figure 7 also illustrates the effect of mol ratio on the amount of coke (figures as in all coke data given in this specification being the weight percentage based on the charging stock). Increasing the mol ratio of hydrogen to charge markedly decreases the amount of coke. Typically we produce from 0.5 to 3% or, more broadly, from 0.1 to 5% of coke per unit of charge.

Typical data corresponding to Figure 7 are given in the following table to illustrate the effect of varying the mol ratio of hydrogen to charge.

Table 4

As illustrated by Figure 8, the optimum mol ratio (or partial pressure) of hydrogen to charge is a function of the severity factor used. Higher severity factors require higher concentrations of hydrogen.

The area in which we find it desirable to work is shown in Figure 8 in which mol ratio is plotted against severity factor and the cross-hatched area is the one in which we prefer to work. Mathematically this area can be defined as lying between the severity factor limits previously given and also lying between the lines defined by the following equations in which M is the mol ratio and S is the severity factor as previously defined:

$$M = \frac{S-875}{125}$$

$$M = \frac{S-890}{15}$$

Optionally the denominator in the first of the above two equations can be 100 instead of 125. The preferred area lies between the preferred severity factor limits (950 and 1075) and between the preferred mol ratio limits of 0.5 and 8.

With reference to the hydrogen used, pure 100% hydrogen is theoretically best but in practice we prefer to use the impure hydrogen produced in our process which contains various amounts of methane, ethane and propane depending on the operating conditions used, the charging stock and the purification system employed. The presence of these hydrocarbons tends to result in higher coke formation but this is not serious over a considerable range. Where we speak of mol ratio of hydrogen to charge we refer to the pure hydrogen content of the gas actually used.

The examples previously given refer to the use of a molybdenum oxide on activated alumina catalyst. A catalyst supported on alumina gel gives still better results. Such a catalyst containing 3.75% MoO₃ by weight can be made as follows:

Dissolve 143 kilograms of ammonium para molybdate (NH₄)₆Mo₇O₂₄·4H₂O in sufficient distilled water to yield 2280 liters of solution. Place 1500 kilograms of granular alumina gel in an apparatus which can be evacuated and add the molybdate solution. Agitate the mixture and then attach to a source of suction and reduce the pressure to 30-40 millimeters of mercury. Then release the vacuum and allow the pressure to rise to atmospheric. Lower the pressure a

second time to the same level and then release again to atmospheric pressure. Repeat this procedure a third time and then drain the remaining liquid from the impregnated gel. Air-dry the latter in screens or other containers using layers of about 1 inch in depth. Then place the dried material in a muffle furnace in a suitable container and heat at a temperature of 1200° F. for one hour. When cooled to room temperature, the product is ready to be used.

Using the catalyst thus prepared the following typical results have been obtained (Example 13) as compared with the results obtained (Example 14) using the catalyst supported on activated alumina, the preparation of which was described earlier in this specification:

Table 5

Octane number of product	82.0	73.5

Chromium catalysts can also be used in place of molybdenum catalysts, particularly catalysts containing from 15 to 40% Cr₂O₃ by weight on alumina. Thus a catalyst containing 25% Cr₂O₃ on 75% of activated alumina can be prepared as follows:

Dissolve 1316 kilograms of chromium trioxide, Cr₂O₃, in sufficient distilled water to give a solution of 1500 liters. Place 1500 kilograms of granular activated alumina in an apparatus which can be evacuated and add the solution of chromium trioxide. Agitate the mixture and then attach to a source of suction and reduce the pressure to 30-40 millimeters of mercury. Then release the vacuum and allow the pressure to rise to atmospheric. Lower the pressure a second time to the same level and then release again to atmospheric pressure. Repeat this procedure a third time and then drain the remaining liquid from the impregnated alumina. Air-dry the latter in screens or other suitable containers using layers of about 1 inch in depth. Then place the dried material in a muffle furnace and heat it at a temperature of 1200° F. for one hour. After cooling the product is ready for use.

Using this latter catalyst the following typical results were obtained:

¹ Gas contained 49.4% H₂ by volume.

All of the foregoing examples are for convenience of comparison based on charging the East Texas heavy naphtha described immediately above Table 1. However, we have applied our process to more than thirty charging stocks with good results. To illustrate the use of varied feed stocks the data of Table 7 below are typical. In Example Number 16 the charge was a Michigan virgin naphtha having an A. P. I. gravity of 61.5. This naphtha had an initial boiling point of 120° F., a 50% boiling point of 270° F., an end point of 396° F. and an octane number of 24.0. In Example Number 17 the charge was a California virgin naphtha having an A. P. I. gravity of 47.0, containing 1.5% olefins and 13.5% aromatics. This naphtha had an initial boiling point of 258° F., a 50% boiling point of 305° F., an end point of 398° F. and an octane number of 57.8. The catalyst used was the molybdenum oxide on activated alumina, the preparation of which is described early in this specification.

Having thus described our process in general terms and the operating conditions which we find give us the new and unexpected results previously pointed out, we turn now to a description of specific embodiments of our invention in terms of apparatus and process flow. This is illustrated in one embodiment in Figure 9 and in another embodiment in Figures 10, 11 and 12.

Figure 9 is a somewhat simplified flow diagram showing the application of our invention to a system using a stationary catalyst bed.

The feed stock which may, for instance, be a fraction containing virgin gasoline and heavier material is charged through line 11 by pump 12 into heater 13 from which it passes to fractionator 14 which may be of the usual bubble plate type. The heater and fractionator are so operated that a fraction of which at least about 75% boils between 200° F. and 450° F. and preferably between 250° F. and 425° F. and which is at least 25% and preferably at least 35% composed of paraffinic hydrocarbons having from 6 to 12 or 14 carbon atoms is withdrawn from trapout plate 15 through valve 16 while the lighter material charged through line 11 passes out from the top of the fractionator through line 17 and can be passed to storage or discharged from the system through valve 18. However, this material, usually corresponding to the valuable lighter fraction of gasoline, can be passed through valve 19 and combined with the product from our catalytic aromatization process. As will be noted, fractionator 14 is provided with the customary reflux coil 20 and can if desired be equipped with a reboiler coil as well. Material heavier than that desired as charging stock to our catalytic aromatization process is withdrawn through valved line 21.

The charge, preferably a heavy naphtha as described, containing at least 25% and preferably

at least 35% of aliphatic hydrocarbons, can come from some other source such as valved line 22, valve 16 being closed. Examples of suitable naphtha charging stocks defined in terms of 10% and 90% distillation points are as follows:

Table 8

	A	B	C	D	E	F	G
10% point	° F. 145	° F. 165	° F. 165	° F. 190	° F. 350	° F. 300	° F. 325
90% point	200	425	290	300	380	425	390

Whatever its source and exact nature, the charge for our process is pumped by means of pump 23 through line 24 and heat exchanger 25 where it is preheated by indirect heat exchange with the hot aromatization products and then passes through line 26 and coil 27 of heater 28 and thence to one or both of reactors 29 which are shown in the form used in a commercial embodiment of our process with catalyst tubes 30 connecting with headers 31 and 32, the space between the tubes being heated to compensate for the endothermicity of the reaction and maintain the required temperature (T). This can be accomplished by passing hot flue gas or other heating medium in through valved line 33 and out through valved line 34.

30 Simultaneously with the introduction of the charge, hydrogen from storage tank 35 and/or recycle hydrogen from the process passes through line 36 and compressors 37 and thence through valve 38 (assuming valve 39 to be closed) and heating coil 40 and thence through valve 41 and line 42 to one or both of reactors 29 along with the heated charge which is now in the vapor phase.

35 Since the reaction is a dehydrogenation and aromatization reaction rather than an hydrogenation reaction and is markedly endothermic the charge and hydrogen are generally heated to temperatures above the desired average temperature (T) in the reactors or catalyst chambers to supply the endothermic heat of reaction, and this is necessarily true if unheated reactors are used, the temperature differential depending on the process conditions and apparatus size and design. To maintain more uniform temperature and minimize any purely thermal conversion the hydrogen can be heated to a higher temperature than the charge and it can, if desired, be injected at multiple points in the catalyst bed.

40 Instead of using coil 27 for heating the charging stock and coil 40 for the hydrogen, valves 38, 39 and 41 can all be opened so that the charging stock and hydrogen pass together through both coils or valves 38 and 41 can be closed and valve 39 opened so that coil 40 is not used (or not present) and the charge and hydrogen are heated together in coil 27.

45 Two reactors 29 are shown. As previously mentioned, the charging stock and hydrogen are passed through one or both of them under the control of valves 43, 44, 45 and 46. Downflow through the catalyst is illustrated and is generally preferred but upflow can likewise be used. Also it will be apparent that a larger number of reactors can and usually will be used in order to provide a suitable regeneration cycle.

50 The charge and hydrogen pass through at least one of reactors 29 under the operating conditions hereinbefore described and thence pass through heat exchanger 25 and cooler 47 to a high pres-

sure separator 48 from which the hydrogen, usually containing some light hydrocarbon gases, passes out through line 49. All or part of this can be withdrawn from the system through valved line 50, particularly at times when it is relatively impure, and the remainder preferably passes to an hydrogen purification system 51 which is only shown generally since it does not constitute any important part of this invention. In the hydrogen purification system hydrocarbon gases and other impurities are removed by one of various methods; for instance, by scrubbing with an absorber oil. This hydrogen purification system can be by-passed by opening valve 52 and closing valve 53. Either all or part of the gases can be sent through the by-pass line. From the purification system and/or from the by-pass line, the hydrogen is recycled through line 36 in part but net hydrogen is withdrawn either through valved line 50, as previously described, or through pressure controlled valve 54 leading to storage tank 35.

High pressure separator 48 can suitably be equipped with dephlegmating coil 55.

The liquid material, including all the gasoline and heavier fractions as well as considerable amounts of normally gaseous hydrocarbons is withdrawn from the bottom of separator 48 through pressure or liquid level controlled valve 56 to heater 57 and thence through line 58 to fractionator 59 which is operated at a lower pressure than separator 48 and the gases lighter than the desired product are withdrawn from the system through pressure controlled valve 60. Part of the hydrogen produced can also be removed at this point. This fractionator 59 is, of course, equipped with a dephlegmating coil 61 and can be equipped with a reboiler coil as well. The desired product is withdrawn through trapout plate 62 and valved line 63. The heavier material, which we sometimes refer to as "polymer" and which is very limited in amount, is withdrawn from fractionator 59 through valved line 64.

As previously described, our process results in considerable reduction in the deposition of coke and other carbonaceous material as compared with prior art dehydrogenation processes operating at atmospheric pressure and/or in the absence of hydrogen. However, it differs from destructive hydrogenation processes in the fact that the catalyst does decrease in activity due to this deposition of coke or other carbonaceous material and it must be regenerated from time to time, usually at intervals of from 25 to 100 hours but sometimes at shorter on-stream intervals, depending on the catalyst used, the severity factor, the mol ratio, the nature of the paraffinic charging stock, etc.

When regeneration is necessary or desirable using the apparatus of Figure 9, one of reactors 29 which needs regeneration is cut out of the system, for instance by closing valves 43 and 45. The system is purged of hydrocarbons by introducing steam, flue gas or other purging medium through valved line 65, passing out of the reactor through valved line 66 to a suitable recovery system (not shown). Air diluted with flue gas or some other gaseous oxidation medium is then passed through the catalyst chamber, for instance by means of valved lines 67 and 68, at controlled temperature as known to the art, to burn off the coke and other carbonaceous material, after which the reactor containing the catalyst thus regenerated can again be put on stream.

In the meantime, of course, the remaining reactor or reactors are on stream so that the process is not interrupted.

While our invention can, as has been described, be used in connection with a stationary catalyst bed or a plurality of stationary catalyst beds, we find that particularly good results can be obtained by the use of a moving catalyst bed and one embodiment of this type of invention is shown in Figures 10, 11 and 12. Apparatus of the Figure 10 type was used in the laboratory in obtaining most of the data given in this specification, although the data of run No. 1083A, for example, were obtained with a stationary catalyst bed.

Turning now to Figure 10 in more detail, a feed, which can have the characteristics previously described, is pumped from feed stock tank 101 by means of pump 102 through coil 103 in heater 104. Simultaneously hydrogen from any suitable source, including recycle hydrogen, if desired, is passed through the same heating coil (as illustrated in Figure 10) although separate heating coils can be used (as in Figure 9). As shown, hydrogen from tank 105 passes through pressure reducing valve 106 and meter 107 and thence through throttle valve 108 into coil 103. From the heater the hot mixed hydrogen and feed stock pass through line 109 to the top of a reaction chamber 110 as will be described in more detail in connection with Figure 11. This reaction chamber consisted, in the laboratory model, of a 7 foot length of 2 inch extra heavy tubing surrounded by an electrically heated lead bath to supply the heat of reaction but for plant use a jacket 111 heated by flue gas introduced through valved line 112 and withdrawn through valved line 113 is preferred.

The granular catalyst of the type previously described is added by means of inlet 114 passing through valves 115 and 116 separated by an injection line 117 for nitrogen, flue gas, or steam to act as a gas lock. The catalyst passes downward through the reaction chamber 110 and the hot charging stock and hydrogen pass concurrently therewith although counter-current flow can likewise be used. The catalyst is supported at the bottom on a rotary feeder 118 which permits it to pass slowly downward through the reaction chamber, thence through valves 119 and 120 separated by a gas lock 121 with intermediate nitrogen or other inert gas injection and thence to a catalyst revivification chamber which is not shown. In this revivification chamber the catalyst is, of course, treated with an hot oxidizing gas to burn off the coke and other carbonaceous material, care being taken to control the temperature so that the catalyst will not be injured. The regenerated catalyst is returned to inlet 114.

Reaction products pass out from the reaction chamber in a manner which will be described in connection with Figure 12 through line 122 and thence to a trap 123, which can be packed with glass wool or the like, where any catalyst carried with the products is deposited and can be removed periodically. The products then go to cooler 124 and high pressure separator 125. In this high pressure separator the hydrogen carrying with it some light hydrocarbon gases is separated from the aromatized naphtha. The gas passes overhead through line 126 and pressure control valve 127 and thence through line 128 to absorber 129 where it is stripped with the usual absorption medium to remove residual val-

uable hydrocarbons. The remaining gas rich in hydrogen is vented through valved line 130. The hydrogen thus vented is substantially in excess of the hydrogen originally introduced. Alternatively excess gas can be removed through valved line 128a and recycled to the reaction chamber.

Turning to the liquid product from high pressure separator 125, this passes through line 131 and pressure or liquid level controlled valve 132 to a low pressure separator 133 in which some additional gas containing not only a little hydrogen and some light hydrocarbons but also an appreciable amount of butane and other valuable light naphtha constituents passes out through line 134, cooler 135 and line 128 to absorber 129 where it is contacted along with the gases from high pressure separator 125 with an absorption medium introduced through line 136 by means of pump 137 and withdrawn through line 138 by means of pump 139 passing through heat exchanger 140 and heater 141 to stripper 142 equipped with the usual reboiler coil 143 and dephlegmating coil 144. The lean oil from the stripper passes through heat exchanger 140 and cooler 145 back to pump 137 and absorber 129 for reuse. The stripper yields an overhead consisting largely of light ends of motor fuel and this passes through line 146 and cooler 147 back to low pressure separator 133. The final product is withdrawn through valved line 148.

Referring now to Figure 11, the granular catalyst from hopper 114 which may be made up predominantly of granules within the range from 2 mesh to 50 mesh, for instance 4 mesh passes through valve 115 which can be continuous or discontinuous in its operation into chamber 149 wherein inert gas is injected to prevent diffusion of naphtha vapors out of the system. Thence the catalyst passes through valve 116, which can often be omitted or left open, into a tapering tube 150 wherein the hot charge and hydrogen introduced through line 109 preheat the catalyst by indirect heat exchange and the hot catalyst passes into reaction chamber 110.

The bottom of this reaction chamber is shown at the top of Figure 12. The catalyst passes by gravity flow out of reaction chamber 110 into a chamber 151 formed by screen 152 having a mesh smaller than the smallest catalyst grains. Catalyst flow is regulated by rotary valve 118 which is operated through shaft 153 by a variable speed motor not shown. The catalyst then passes through valve 119, which can in some cases be left open, into gas lock chamber 154 and thence through continuous or intermittent valve 120 to the regeneration system.

Having described our invention what we desire to claim is:

1. In a cyclic catalytic process including alternating on-stream and regeneration periods for the production of aromatic compounds and hydrogen from paraffinic hydrocarbons involving contacting during the on-stream period a hydrocarbon mixture containing at least 35% of paraffinic hydrocarbons of from 6 to 12 carbon atoms with a dehydrogenating and cyclizing catalyst at an elevated temperature and regulating the flow of said hydrocarbons over the catalyst with reference to the temperature maintained below the rate sufficient merely to convert naphthenes to aromatics and at a sufficiently low rate largely to dehydrogenate and cyclize said paraffinic hydrocarbons to aromatics and accompanied by the net production of hydrogen and a carbonaceous deposit on the catalyst, the method of decreasing the quantity of carbonaceous material deposited on the catalyst thereby increasing the feasible on-stream period for said dehydrogenation and cyclization reaction and effecting a corresponding increase in yield of the desired products, which consists in maintaining a pressure in said reaction zone of from 30 pounds to about 450 pounds per square inch gage and adding hydrogen to said reaction zone in an amount ranging from 0.5 mol to 8 mols of hydrogen per mol of said hydrocarbon mixture and further restricted within the above range to a mol ratio determinable by the particular temperature and rate of flow of charging stock employed, the lower limit of said mol ratio being that defined by the equation
- $$M = \frac{S-875}{125}$$
- 20 and the upper limit by the equation
    - 25
$$M = \frac{S-890}{15}$$

in which S represents a severity factor defined by the equation

$$S = T + 100 \log_{10} F$$

in which T represents the reaction temperature employed maintained within a range not less than 875° and not more than 1075° F.; and F represents the time factor being the number of hours required to flow one volume of charge measured on the liquid basis through one volume of catalyst space and being maintained within the range between 0.1 and 25, the particular temperature and time factor employed within said ranges being related in such manner that S has a value between 925 and 1100 adapted to effect said dehydrogenation and cyclization reaction.

    - 30 2. A process for converting a naphtha charging stock rich in aliphatic hydrocarbons of from 6 to 12 carbon atoms into hydrogen and a motor fuel or motor fuel component rich in aromatic hydrocarbons involving a cyclic catalytic operation including alternating on-stream and regeneration periods which comprises contacting during the on-stream period said naphtha charging stock in the vapor phase with a dehydrogenating and cyclizing catalyst at a temperature between 875° F. and 1075° F. maintained by supplying the endothermic heat of reaction to the catalyst contact zone, at a time factor of from 0.1 to 25, where the time factor is the number of hours required to pass one volume of charge measured as liquid through one volume of catalyst space, the time factor being selected within said range relative to the particular temperature maintained so as to effect dehydrogenation and cyclization of said aliphatic hydrocarbons and at a pressure of from 30 pounds per square inch gage to about 450 pounds per square inch gage in the presence of added hydrogen in an amount ranging from 0.4 mols of hydrogen per mol of said charging stock to 9 mols of hydrogen per mol of said charging stock, and removing net produced hydrogen from the process, whereby the feasible on-stream period for said conversion is substantially increased and there is produced from said charging stock a net yield of hydrogen and a high yield of highly aromatic material boiling within the gasoline boiling point range, having a high octane number and an A. P. I. gravity less than the A. P. I. gravity of such portion of said charging stock as boils within the gasoline boiling point range.

3. A process for converting a naphtha charging stock rich in aliphatic hydrocarbons into hydrogen and a motor fuel or motor fuel component rich in aromatic hydrocarbons involving a cyclic catalytic operation including alternating on-stream and regeneration periods which comprises contacting during the on-stream period said naphtha charging stock in the vapor phase with a dehydrogenating and cyclicizing catalyst at a temperature (T) between 875° F. and 1075° F. maintained by supplying the endothermic heat of reaction to the catalyst contact zone, at a time factor of from 0.1 to 25, where the time factor (F) is the number of hours required to pass one volume of charge measured as liquid through one volume of catalyst space, at a severity factor (S) defined by the equation

$$S = T + 100 \log_{10} F$$

lying between 925 and 1100 and sufficiently high to effect the conversion of aliphatic hydrocarbons to aromatic hydrocarbons, and at a pressure of from 30 pounds per square inch gage to about 450 pounds per square inch gage in the presence of added hydrogen in an amount ranging from 0.4 mols of hydrogen per mol of said charging stock to 8 mols of hydrogen per mol of said charging stock, the mol ratio of hydrogen to charging stock being selected on the basis of the severity factor in such manner that the mol ratio is not less than that defined by the equation

$$M = \frac{S-875}{125}$$

and not more than that defined by the equation

$$M = \frac{S-890}{15}$$

and removing net produced hydrogen from the process, whereby the feasible on-stream period for said conversion is substantially increased and there is produced from said aliphatic naphtha charging stock a net yield of hydrogen and a high yield of highly aromatic material boiling within the gasoline boiling point range, having a high octane number and an A. P. I. gravity less than the A. P. I. gravity of such portion of said charging stock as boils within the gasoline boiling point range.

4. A process for converting aliphatic hydrocarbons present in a naphtha charging stock into hydrogen and aromatic hydrocarbons involving a cyclic catalytic operation including alternating on-stream and regeneration periods which comprises flowing during the on-stream period said naphtha charging stock in the vapor phase at a temperature (T) between 875° F. and 1025° F. through a reaction zone in contact with a dehydrogenating and cyclicizing catalyst comprising an oxide of a metal selected from the left hand columns of groups IV, V and VI of the periodic table, maintaining said temperature by supplying the endothermic heat of reaction to the catalyst contact zone, regulating the rate of flow of said naphtha charging stock through said dehydrogenating and cyclicizing catalyst to provide a time factor between 0.1 and 25, where time factor (F) is the number of hours required to flow one volume of charge measured as liquid through one volume of catalyst space, maintaining the severity factor (S) defined by the equation

$$S = T + 100 \log_{10} F$$

between 925 and 1075 and sufficiently high to effect the conversion of aliphatic hydrocarbons

to aromatic hydrocarbons, maintaining the pressure in the reaction zone at from 30 pounds per square inch gage to 300 pounds per square inch gage in the presence of hydrogen introduced into the reaction zone in an amount ranging from 0.5 mol of hydrogen per mol of said charging stock to 8 mols of hydrogen per mol of said charging stock, the mol ratio of hydrogen to charging stock being selected within this range on the basis of the severity factor in such manner that the mol ratio is not less than that defined by the equation

$$M = \frac{S-875}{125}$$

and not more than that defined by the equation

$$M = \frac{S-890}{15}$$

and removing net produced hydrogen from the process, whereby the feasible on-stream period for said conversion is substantially increased and said aliphatic hydrocarbons are converted in large measure into aromatic hydrocarbons boiling within the gasoline boiling point range and having high octane numbers and whereby a net yield of hydrogen and a product boiling within the gasoline boiling point range having an A. P. I. gravity less than the A. P. I. gravity of such portion of said charging stock as boils within the gasoline boiling point range are produced.

5. A process for converting a naphtha charging stock containing a substantial amount of aliphatic hydrocarbons into hydrogen and a motor fuel or motor fuel component rich in aromatic hydrocarbons involving a cyclic catalytic operation including alternating on-stream and regeneration periods which comprises contacting during the on-stream period said naphtha charging stock in the vapor phase in a reaction zone in the presence of added hydrogen with a dehydrogenating and cyclicizing catalyst comprising an oxide of a metal selected from the left hand column of group VI supported on alumina at a temperature (T) between 890° F. and 1025° F., supplying heat to said reaction zone in addition to that necessary to heat said charging stock and said added hydrogen to the desired temperature (T) thus supplying the endothermic heat of reaction, at a time factor of from 0.2 to 20, where time factor (F) is the number of hours required to contact one volume of charge measured as liquid through one volume of catalyst space, at a severity factor (S) defined by the equation

$$S = T + 100 \log_{10} F$$

lying between 975 and 1075 adapted to convert aliphatic hydrocarbons to aromatic hydrocarbons, and at a pressure of from 50 pounds per square inch gage to 250 pounds per square inch gage in the presence of hydrogen added in an amount ranging from 0.5 mol of hydrogen per mol of said charging stock to 8 mols of hydrogen per mol of said charging stock, the mol ratio of hydrogen to charging stock being selected on the basis of the severity factor in such manner that the mol ratio is not less than that defined by the equation

$$M = \frac{S-875}{125}$$

and not more than that defined by the equation

$$M = \frac{S-890}{15}$$

and removing net produced hydrogen from the

process, whereby the feasible on-stream period for said conversion is substantially increased and said aliphatic hydrocarbons are converted in large measure into aromatic hydrocarbons boiling within the gasoline boiling point range and having high octane numbers and whereby a net yield of hydrogen and a product boiling within the gasoline boiling point range having an A. P. I. gravity less than the A. P. I. gravity of said charging stock are produced.

6. A process for converting a naphtha charging stock containing a substantial amount of aliphatic hydrocarbons into hydrogen and a motor fuel or motor fuel component rich in aromatic hydrocarbons involving a cyclic catalytic operation including alternating on-stream and regeneration periods which comprises contacting said naphtha charging stock in the vapor phase in a reaction zone in the presence of added hydrogen with a dehydrogenating and cyclizing catalyst comprising molybdenum oxide supported on alumina at a temperature (T) between 890° F. and 1025° F., supplying heat to said reaction zone in addition to that necessary to heat said charging stock and said added hydrogen to the desired temperature (T) thus supplying the endothermic heat of reaction, at a time factor of from 0.2 to 20, where time factor (F) is the number of hours required to contact one volume of charge measured as liquid through one volume of catalyst space, at a severity factor (S) defined by the equation

$$S = T + 100 \log_{10} F$$

lying between 975 and 1075 adapted to convert aliphatic hydrocarbons to aromatic hydrocarbons, and at a pressure of from 50 pounds per square inch gage to 300 pounds per square inch gage in the presence of hydrogen added in an amount ranging from 0.5 mol of hydrogen per mol of said charging stock to 8 mols of hydrogen per mol of said charging stock, the mol ratio of hydrogen to charging stock being selected on the basis of the severity factor in such manner that the mol ratio is not less than that defined by the equation

$$M = \frac{S - 875}{125}$$

and not more than that defined by the equation

$$M = \frac{S - 890}{15}$$

and removing net produced hydrogen from the process, whereby the feasible on-stream period for said conversion is substantially increased and said aliphatic hydrocarbons are converted in large measure into aromatic hydrocarbons boiling within the gasoline boiling point range and having high octane number and whereby a net yield of hydrogen and a product boiling within the gasoline boiling point range having an A. P. I. gravity at least 3° A. P. I. less than the A. P. I. gravity of that part of said charging stock which boils within the gasoline boiling point range are produced.

7. A process for converting a naphtha charging stock containing a large amount of aliphatic hydrocarbons into hydrogen and an aromatic motor fuel or motor fuel component involving a cyclic catalytic operation including alternating on-stream and regeneration periods which comprises flowing during the on-stream period said naphtha charging stock in the vapor phase at a temperature (T) between 875° F. and 1025° F. through a moving bed of a dehydrogenating and

cyclizing catalyst consisting essentially of molybdenum oxide adsorbed on alumina, maintaining said temperature by supplying the endothermic heat of reaction to the catalyst contact zone regulating the rate of flow of said charging stock through said moving bed of catalyst to provide a time factor between 0.1 and 25, where time factor (F) is the number of hours required to contact one volume of charging stock measured as liquid through one volume of catalyst space, maintaining the severity factor (S) defined by the equation

$$S = T + 100 \log_{10} F$$

15 between 925 and 1075 and sufficiently high to effect the conversion of aliphatic hydrocarbons to aromatic hydrocarbons, maintaining the pressure at which said catalyst and said charging stock are contacted between 30 pounds per square inch gage and about 450 pounds per square inch gage in the presence of hydrogen introduced into the reaction zone in an amount ranging from 0.5 mol of hydrogen per mol of said charging stock to 9 mols of hydrogen per mol of said charging stock, the mol ratio of hydrogen to charging stock being selected within this range on the basis of the severity factor in such manner that the mol ratio is not less than that defined by the equation

$$30 \quad M = \frac{S - 875}{100}$$

and not more than that defined by the equation

$$M = \frac{S - 890}{15}$$

35 and removing net produced hydrogen from the process whereby the feasible on-stream period for said conversion is substantially increased and aliphatic hydrocarbons present in said charging stock are converted in large measure into aromatic hydrocarbons boiling within the gasoline boiling point range and having high octane numbers and whereby a net yield of hydrogen and a product boiling within the gasoline boiling point range having an A. P. I. gravity less than the A. P. I. gravity of such portion of said charging stock as boils within the gasoline boiling point range are produced.

40 8. A process according to claim 7 in which said molybdenum oxide constitutes from 2% to 10% by weight of the total catalyst including the support.

45 9. A process for converting a naphtha charging stock rich in aliphatic hydrocarbons into hydrogen and a motor fuel or motor fuel component rich in aromatic hydrocarbons involving a cyclic catalytic operation including alternating on-stream and regeneration periods which comprises contacting during the on-stream period said aliphatic naphtha charging stock in the vapor phase with a dehydrogenating and cyclizing catalyst at a temperature (T) between 875° F. and 1075° F., maintained by supplying the endothermic heat of reaction to the catalyst contact zone, at a time factor of from 0.1 to 25, where the time factor (F) is the number of hours required to pass one volume of charge measured as liquid through one volume of catalyst space, at a severity factor (S) defined by the equation

$$70 \quad S = T + 100 \log_{10} F$$

75 lying between 925 and 1100 and sufficiently high to effect the conversion of aliphatic hydrocarbons to aromatic hydrocarbons, and at a pres-

sure of from 30 pounds per square inch gage to about 450 pounds per square inch gage in the presence of added hydrogen in an amount ranging from 0.4 mol of hydrogen per mol of said charging stock to 9 mols of hydrogen per mol of said charging stock, the mol ratio of hydrogen to charging stock being selected on the basis of the severity factor in such manner that the mol ratio is not less than that defined by the equation

$$M = \frac{S-875}{100}$$

and not more than that defined by the equation

$$M = \frac{S-890}{15}$$

and removing net produced hydrogen from the process, whereby the feasible on-stream period for said conversion is substantially increased and there is produced from said naphtha charging stock a net yield of hydrogen and a high yield of highly aromatic material boiling within the gasoline boiling point range, having a high octane number and whereby said catalyst is fouled by coke-like carbonaceous matter at a rate much less than that for ordinary dehydrogenation processes but much greater than that for hydrogenation processes, and periodically regenerating said catalyst by contacting it with a hot oxygen-containing gas.

10. A process for converting a naphtha charging stock containing a large amount of paraffinic hydrocarbons into hydrogen and a motor fuel or motor fuel component rich in aromatic hydrocarbons involving a cyclic catalytic operation including alternating on-stream and regeneration periods which comprises contacting during the on-stream period said paraffinic naphtha charging stock in the vapor phase with a dehydrogenating and cyclizing catalyst at a temperature (T) between 875° F. and 1025° F., maintained by supplying the endothermic heat of reaction to the catalyst contact zone, at a time factor of from 0.1 to 25, where the time factor (F) is the number of hours required to pass one volume of charge measured as liquid through one volume of catalyst space, at a severity factor (S) defined by the equation

$$S = T + 100 \log_{10} F$$

lying between 925 and 1075 and sufficiently high to effect the conversion of aliphatic hydrocarbons to aromatic hydrocarbons, and at a pressure of from 30 pounds per square inch gage to about 450 pounds per square inch gage in the presence of added hydrogen in an amount ranging from 0.5 mol of hydrogen per mol of said charging stock to 9 mols of hydrogen per mol of said charging stock, the mol ratio of hydrogen to charging stock being selected on the basis of the severity factor in such manner that the mol ratio is not less than that defined by the equation

$$M = \frac{S-875}{125}$$

and not more than that defined by the equation

$$M = \frac{S-890}{15}$$

and removing net produced hydrogen from the process, whereby the feasible on-stream period for said conversion is substantially increased and there is produced from said aliphatic naphtha charging stock a net yield of hydrogen and a high yield of highly aromatic material boiling

within the gasoline boiling point range, having a high octane number and an A. P. I. gravity less than the A. P. I. gravity of such portion of said charging stock as boils within the gasoline boiling point range, and whereby said catalyst is fouled by coke-like carbonaceous matter at a rate much less than that for ordinary dehydrogenation processes but much greater than that for hydrogenation processes, and following the

10 on-stream period regenerating said catalyst by contacting it with a hot oxygen-containing gas.

11. A process for converting a naphtha charging stock containing at least 35% of paraffinic hydrocarbons into hydrogen and a motor fuel or 15 motor fuel component containing at least 35% of aromatic hydrocarbons involving a cyclic catalytic operation including alternating on-stream and regeneration periods which comprises contacting during the on-stream period said naphtha charging stock in the vapor phase at a temperature (T) between 875° F. and 1025° F., with a dehydrogenating and cyclizing catalyst comprising an oxide of a metal selected from the left hand columns of groups IV, V and VI of the periodic table, maintaining said temperature by applying the endothermic heat of reaction to the catalyst contact zone, regulating the rate of flow of said charging stock through said catalyst to provide a time factor between 0.1 and 25, 30 where time factor (F) is the number of hours required to contact one volume of charge measured as liquid through one volume of catalyst space, maintaining the severity factor (S) defined by the equation

$$S = T + 100 \log_{10} F$$

between 925 and 1075 and sufficiently high to effect the conversion of aliphatic hydrocarbons to aromatic hydrocarbons, maintaining the pressure of said contacting operation at from 30

40 pounds per square inch gage to about 450 pounds per square inch gage, introducing hydrogen previously produced by the reaction into the reaction zone in an amount ranging from 0.5 45 mol of hydrogen per mol of said charging stock to 9 mols of hydrogen per mol of said charging stock, the mol ratio of hydrogen to charging stock being selected within this range on the basis of the severity factor in such manner that 50 the mol ratio is not less than that defined by the equation

$$M = \frac{S-875}{125}$$

55 and not more than that defined by the equation

$$M = \frac{S-890}{15}$$

recycling a part of the hydrogen produced by the reaction to the reaction zone and removing 60 net produced hydrogen from the process, whereby the feasible on-stream period for said conversion is substantially increased and said paraffinic hydrocarbons are converted in large measure into aromatic hydrocarbons boiling within the gasoline boiling point range and having high octane numbers and whereby a net yield of hydrogen and a product boiling within the gasoline boiling point range having an A. P. I. gravity less than 65 70 the A. P. I. gravity of such portion of said charging stock as boils within the gasoline boiling point range are produced.

12. A process as defined in claim 9 wherein said naphtha charging stock comprises a cracked naphtha and wherein said pressure is maintained

in the range of about 30 to 250 pounds per square inch gauge.

13. A process as defined in claim 9 wherein said charging stock consists essentially of a virgin petroleum naphtha and said pressure is maintained at a minimum value in excess of 100 lbs. per square inch gauge.

14. A cyclic catalytic process of converting a naphtha fraction rich in straight chain hydrocarbon compounds containing 6 or more carbon atoms into hydrogen and a highly aromatic product suitable for use as a motor fuel, which comprises adding free hydrogen to said fraction and contacting the resultant mixture at an elevated temperature with the dehydrogenating and cyclizing catalyst, maintaining a rate of flow of said mixture over the catalyst regulated with respect to other variable operating conditions sufficiently low to largely dehydrogenate and cyclize said straight chain hydrocarbons to aromatics, said conversion being accompanied by the net production of hydrogen and the deposition of a deactivating carbonaceous material on the catalyst, said added free hydrogen being introduced in amount sufficient to maintain a feed ratio of hydrogen to naphtha of about 0.5 to 8.0 mols per mol of naphtha, and maintaining the combined partial pressures of said hydrogen and naphtha in the reaction zone within the range of from 30 to about 450 pounds per square inch gauge, thereby effecting an enhanced yield of aromatic compounds and a substantial decrease in the quantity of said carbonaceous deposit produced per unit of naphtha charged and a corresponding increase in the feasible on-stream period before regeneration of the catalyst is required compared with a similar operation except in the absence of said added hydrogen and maintained pressure, continuing the passage of said naphtha vapors and hydrogen over the catalyst until the carbonaceous deposit thereon accumulates to an extent sufficient to decrease the conversion of aliphatic compounds to hydrogen and aromatics to an undesired extent, and thereafter regenerating the catalyst for reuse in said conversion by removal of the carbonaceous deposit therefrom.

15. In a process for producing hydrogen and aromatic hydrocarbons from aliphatic hydrocarbons having boiling points within the boiling point range of naphtha wherein, during an on-stream period, a stream containing aliphatic hydrocarbons is passed in contact with a dehydrogenating and cyclizing catalyst under conditions adapted to convert said hydrocarbons to hydrogen and aromatic hydrocarbons and the flow of said hydrocarbons in contact with the catalyst is continued until the conversion to aromatics and hydrogen decreases to an undesired extent due to an accumulation of carbon-

aceous material on the surface of the catalyst produced by side reactions incident to said conversion, and thereafter during a regeneration period, the activity of said catalyst for said conversion is revivified, and said on-stream conversion and catalyst revivification periods are alternately and continuously repeated in a cyclic operation, the improved method whereby an enhanced yield of the desired aromatic products is produced, comprising adding free hydrogen to said stream of aliphatic hydrocarbons in an amount not less than about $\frac{1}{2}$ mol volume and not in excess of about 8 mol volumes per mol volume of hydrocarbon feed whereby a concentration of free hydrogen in substantial excess of the free hydrogen concentration resulting from the conversion alone is maintained in the catalytic contacting zone, and maintaining said zone under a pressure of not less than about 30 and not in excess of about 450 lbs. per square inch gauge.

16. In a process for producing hydrogen and aromatic hydrocarbons from aliphatic hydrocarbons having boiling points within the boiling point range of naphtha wherein, during an on-stream period, a stream containing aliphatic hydrocarbons is passed in contact with a dehydrogenating and cyclizing catalyst under conditions adapted to convert said hydrocarbons primarily to hydrogen and aromatic hydrocarbons with incidental production due to side reactions of appreciable but limited quantities of olefinic normally liquid hydrocarbons and cracked normally gaseous hydrocarbons and the flow continued of said hydrocarbons in contact with the catalyst until the conversion to aromatics and hydrogen decreases to an undesired extent due to an accumulation of solid carbonaceous material on the surface of the catalyst also produced by said side reactions, and thereafter, during a regeneration period, the activity of said catalyst for said conversion is revivified, and said on-stream conversion and catalyst revivification periods are alternately and continuously repeated in a cyclic operation, the improved method whereby an enhanced yield of the desired aromatic products is produced, comprising adding free hydrogen to said stream of aliphatic hydrocarbons in an amount not less than about $\frac{1}{2}$ mol volume and not in excess of about 8 mol volumes per mol volume of hydrocarbon feed whereby a concentration of free hydrogen in substantial excess of the free hydrogen concentration resulting from the conversion alone is maintained in the catalytic contacting zone, and maintaining said zone under a pressure of not less than about 30 and not in excess of about 450 lbs. per square inch gauge.
